UNITED STATES PATENT OFFICE.

DUVAL LA CHAPELLE, OF NYACK, NEW YORK.

DESIGN FOR A HULL OF A GLIDING BOAT.

49,358.

Specification for Design.

Patented July 11, 1916.

Application filed January 13, 1916. Serial No. 71,984. Term of patent 14 years.

To all whom it may concern:

Be it known that I, DUVAL LA CHAPELLE, a citizen of the United States, and a resident of Nyack, in the county of Rockland and State of New York, have invented a new, original, and ornamental Design for the Hull of a Gliding Boat, of which the following is a specification, reference being had to the accompanying drawings, forming a part thereof.

Figure 1 is a perspective view of the top or inside of the hull; and Fig. 2 is a similar view of the bottom of the hull, showing my new design.

Among the novel and ornamental charac-

teristics of this new and ornamental design for the hull of a gliding boat is the construction of the front portion of a generally pointed or triangular shape, the apex of the triangle being in the lead, but which triangle is made up of a plurality of substantially right angular corners or portions along each side, as viewed in plan.

I claim:—

The ornamental design for the hull of a gliding boat, as shown and described.

DUVAL LA CHAPELLE.
